BICYCLE FRAME

Philip Steller, 75 Longfellow Road,
Great Neck, N.Y. 11023

Continuation-in-part of design application Ser. No. 19,459,
Oct. 8, 1969. This application Jan. 18, 1971, Ser. No.
107,608

Term of patent 14 years

Int. Cl. D12—11

U.S. Cl. D90—8

FIG. 1.

FIG. 2.

FIG. 3.

FIG. 4.

FIG. 5.

FIG. 1 is a side elevational view of a bicycle frame showing my new design;

FIG. 2 is a top plan view thereof;

FIG. 3 is a bottom plan view thereof;

FIG. 4 is an end view thereof taken from the left;

FIG. 5 is an end view thereof taken from the right.

This application is a continuation-in-part of my co-pending application Ser. No. D. 19,459, filed Oct. 8, 1969, now abandoned.

I claim:

The ornamental design for a bicycle frame, substantially as shown and described.
